[57] CLAIM

The ornamental design for a bed linen, as shown and described.

DESCRIPTION

FIG. 1 is a top plan view of a bed linen showing my new design;

FIG. 2 is an end elevational view thereof, the opposite end being identical in appearance;

FIG. 3 is a side elevational view thereof, the opposite side being identical in appearance;

FIG. 4 is a bottom plan view thereof;

FIG. 5 is a top plan view of a bed linen showing an alternate embodiment of my new design;

FIG. 6 is an end elevational view thereof, the opposite end being identical in appearance;

FIG. 7 is a side elevational view thereof, the opposite side being identical in appearance; and

FIG. 8 is a bottom plan view thereof.
